UNITED STATES PATENT OFFICE.

LEWIS F. DAVIS, OF BOWIE, TEXAS.

CISTERN-CLEANER.

1,265,434.

Specification of Letters Patent. Patented May 7, 1918.

Application filed May 25, 1917. Serial No. 170,903.

To all whom it may concern:

Be it known that I, LEWIS F. DAVIS, a citizen of the United States, residing at Bowie, in the county of Montague, State of Texas, have invented certain new and useful Improvements in Cistern-Cleaners; and I do hereby declare the following to be a full, clear, and exact description of the invention, such as will enable others skilled 10 in the art to which it appertains to make and use the same.

This invention relates to improvements in cistern cleaners and particularly to suction cleaners.

15 One object of the present invention is to provide a device of this character whereby the mud and sediment at the bottom of the cistern may be quickly and easily removed without stirring up said mud and sediment 20 with the consequent contamination of the water.

Another object is to provide a device of this character which can be easily lowered into the cistern and moved over the bottom 25 thereof to gather the mud and sediment without necessity of the device being sunk into the mud and sediment and causing the same to rise in the water.

Other objects and advantages will be apparent from the following description when taken in connection with the accompanying drawing.

In the drawing:

Figure 1 is a side elevation of my improved cistern cleaner.

Fig. 2 is a vertical longitudinal sectional view taken on the line 2—2 of Fig. 1.

Fig. 3 is a horizontal sectional view taken on the line 3—3 of Fig. 1, enlarged.

40 Fig. 4 is a horizontal sectional view taken on the line 4—4 of Fig. 1.

Referring particularly to the accompanying drawing 10 represents an elongated cylindrical casing having a top member 11 and 45 a bottom member 12. On the top member there are secured a pair of L-shaped brackets 13 and disposed between the upright portions of these brackets, and secured thereto, is the lower end of a rod section 14.

50 Hinged to the upper end of this section is a second section 15, one side of the lower section carrying a hook 16 for engagement with an eye carried by the upper section, for the purpose of holding the hinge joint from moving when the device is lowered into the cistern. Other sections may be similarly

connected above the sections shown, according to the depth of the cistern or well to be cleaned. In the top member, at one side of the center thereof, there is formed an 60 opening 17, and secured within this opening, and extending vertically above the top, is a short tube 18. Within this tube is disposed a stopper 19. Disposed vertically through the stopper is a rod 20, having on 65 its lower end a disk 21 to prevent the stopper being pulled up too far, and on the upper end of the rod is formed an eye to which is connected one end of a cord or wire 22, said eye being shown at 23. This cord or 70 wire extends upwardly to the top of the cistern and is adapted to be pulled to lift the stopper from the tube, for a purpose which will be referred to later. In the bottom of the casing there is formed a central opening 24, and within the casing, and mounted 75 on the bottom is a flap valve 25, which is adapted to control the said opening 24.

In the operation of the device, the rod sections are properly locked together, and 80 the casing lowered into the cistern until it rests on the bottom, or slightly thereabove. The stopper is securely fitted in the tube before the casing is lowered, and when the casing is at the bottom of the cistern, the 85 cord is pulled to remove the stopper, when the air in the casing will escape through the tube thus creating suction in the casing which will be strong enough to lift the flap valve and permit the mud and sediment to 90 be drawn up into the casing. When the casing is full of mud and sediment, together with some water which necessarily enters the casing, the stopper will automatically seat itself in the tube. The casing is then 95 pulled from the cistern and the contents removed therefrom.

Particular attention is called to the fact that the casing does not have to touch the bottom of the cistern and thus stir up the 100 mud, but is moved about at a slight distance above the bottom, thereby preventing the contamination of the water, the water being immediately usable after the cistern has been cleaned.

105 What is claimed is:

A cistern cleaner including a casing, a valve in the bottom thereof, a rod connected to the top of the casing for lowering the casing into the cistern, a vertical tube carried by the top of the casing and communicating with the interior thereof, a tightly 110

fitting stopper in the tube, a vertical rod extending longitudinally through the stopper and secured therewithin, a flexible element connected to the upper end of the rod for lifting the stopper from the tube, and a stop disk carried by the lower end of the rod and disposed within the casing and spaced below the upper wall of the casing whereby when the said stopper is entirely removed

from the tube said disk will engage said 10 upper wall and prevent the loss of the stopper.

In testimony whereof I affix my signature in the presence of two witnesses.

LEWIS F. DAVIS.
